COMBINED DISPLAY AND SHIPPING BOX

Meyer M. Soybel, Brooklyn, N. Y., assignor to International Folding Paper Box Co., Inc., North Bergen, N. J., a corporation of New Jersey

Application October 8, 1936, Serial No. 104,567

4 Claims. (Cl. 206—44)

This invention relates to collapsible combined display and shipping boxes, and particularly to that type of box in which articles are packed for shipment, and which may be opened by the recipient for the display of the contents.

The invention contemplates the provision of a simple but efficient one-piece box having a collapsible container part provided with a protecting ledge, and with a display cover part adapted to be raised to display the contents and self-maintained when opened, in an inclined position.

The invention further contemplates the provision of a box in which only one flap is glued and which is provided with an efficient lock for the end flaps automatically holding said flaps in place against opening when said flaps have been arranged in place.

The invention further contemplates the provision of a display and shipping box made from a blank which need be imprinted on one face only, the box, when folded from the blank, having printed matter on both faces of the cover and on all its exposed outer surfaces.

The invention further contemplates the provision of a one-piece display and shipping box which is so designed that it may be collapsed for shipment and easily folded into shape to receive its contents, and which has suitable, efficient but simple holding means for the cover, and bracing means for the top wall of the container part.

The various objects of the invention will be clear from the description which follows and from the drawing, in which—

Fig. 1 is a perspective view of the box in the display position thereof, the contents, however, being omitted.

Fig. 2 is a plan view of the blank from which the box is folded, it being understood that after the edge flap has been secured in place, the box may be readily collapsed to occupy an area whose length is that of the cover added to the lengths of the end flaps, and whose width is that of the cover added to the width of one side of the box.

Fig. 3 is a vertical fragmentary section of an end of the box taken on the line 3—3 of Fig. 1 and showing particularly the locking means for the flaps.

Fig. 4 is an enlarged fragmentary perspective view of the locking means for the flaps.

Fig. 5 is a vertical cross section of the box showing the bracing means for the ledge, and the cover holding tab.

In the practical embodiment of the invention which has been shown by way of example, the box is formed of the one-piece blank 10, the finally

exposed finished surface 11 of which is the under surface as viewed in Fig. 2. The surface 11 may be imprinted substantially throughout its area with the desired illustrations and/or indicia 12, while the other surface of the blank remains unprinted. When the blank is folded, however, both faces of the cover 20 display the printed matter.

The rectangular portions 13 and 14 of the blank 10 which form the cover 20, are folded about the fold line 15 to form the integral bend 16 at the free edge of the cover and to arrange the outermost edge 17 of the blank adjacent the upper fold line 18 of the rear wall 19. Said portions 13 and 14 are secured together with the imprinted surfaces thereof outermost to form the stiffened 15 and comparatively rigid cover 20 of two thicknesses of material. Both faces of the cover therefore, display printed matter 12.

From the rear wall 19 extends integrally the rear side flaps 21, 22, foldable at right angles to the wall 19, and which will later be more fully described. The bottom 23 of the box is limited by the rear fold 24 and the front fold 25 thereof. The front wall 26 extends between the fold lines 25 and 27 and is provided with the front side flaps 28 and 29 extending outwardly therefrom and foldable respectively about the fold lines 30 and 31. The top wall 32 of the container part of the box extends between the fold lines 27 and 59, and is provided with a cut-out portion 33, of the desired shape to provide adequate display of the contents, the remainder of the top wall holding the contents suitably in place during shipping.

The quadrant projections 34 and 35 may be provided, if desired, at the front sides of said cut-out 35 and to extend from the continuous ledge 36 around the remainder of the cut-out. The edge flap 31 at the rear edge of the top wall 32 is foldable about the fold line 59, and is gummed, pasted or otherwise suitably secured to the rear wall 19 with the fold lines 59 and 18 co-incident, after the box has been printed, and when it is ready to be shipped in its collapsed state. Projecting from the top wall 32 are the end flaps 38 and 39 which are preferably identical. Each of said flaps 45 is of substantially the same length as the side flaps 21, 22, 28 and 29, but is subdivided into an end forming portion 40 foldable about the fold line 41 to form an end of the box, and a bottom engaging portion 42 foldable about the fold line 43 and into contact with the bottom wall 23. The free corners of the bottom engaging portion 42 are preferably beveled as at 44.

As shown in Fig. 2, the material removed to form the cut-out 33 may be cut by the severing 55

cut 60 and the end severing cuts 61 and 62 to form flaps 63 and 64 bendable about the respective fold lines 65 and 66 and also bendable about the fold lines 67 and 68. That portion 69 of the flap 63 between the fold lines 67 and 65 is bent under the adjacent portion of the ledge 36 about the fold line 67, while the remaining part 63 of said flap is bent about the fold line 65 into upright position and against the front wall 26, and thereby serves as a brace and support for the ledge. Similarly, the flap 64 has one portion 72 thereof bent underneath the adjacent portion or rear part of the ledge and the remainder thereof again bent into upright position against the rear wall 19.

To provide means for holding the cover down on the top wall 32, a slit as 75 may be made at about the center of the fold line 27 to receive a suitable tab formed on the cover 20. Preferably, 20 said tab is outlined by the severing cut 76 terminating at the fold line 15 to define the tab 77 which may be lifted from the part 13 of the blank and inserted through the slit 75. Said tab 77 is preferably wider at its lower edge than 25 at its upper edge and is hinged to the outer part 14 of the cover when lifted out of the part 13.

Locking means are provided for automatically securing the end flaps 40 in place when the bottom engaging portions 42 thereof have been inserted into the interior of the container part 30 and in contact with the bottom 23. Said means comprises the pair of recesses 45, 46 extending toward each other inwardly of the edges of the flaps 38, 39 and being each provided with sides 35 47, 48 converging slightly inwardly, said sides being joined by the substantially semicircular end edge portion of the recess 49. The fold line 43 is spaced from the edges 47 of the recess, a distance substantially equal to the thickness of 40 the paper from which the blank is made.

Each of the outer portions of the side flaps 21, 22, 28 and 29 is reduced in width along one of its edges beginning at a point as 50 and extending to the outermost end of the flap. Said point 50 is spaced from the fold line of the flap a distance substantially equal to the lengths of the recesses 45 and 46. From the point 50, extends the outwardly inclined edge 51 meeting the edge 52 of the flap, which edge 52 is in alignment with the adjacent fold line 24 or 25, and forms the wider part 53 of the flap.

It will be seen that after the end flap 37 has been secured in place as above described, the sides 19 and 26 may be raised from their collapsed positions into upright position, whereby 55 the bottom 10 and top wall 32 are horizontal, the side flaps being arranged in vertical position. The side flaps may then be folded toward each other in pairs, whereafter the end portion of 60 the flap 39 may be arranged to cover the side flaps, and the bottom portion 42 may be tucked underneath the side flaps and into contact with the bottom 10. As said portion 42 is tucked in, the enlarged portion 53 of the said flap moves into 65 its corresponding recess 45 or 46, and after the edge 47 of the indent is forced past the portion 52, said portion 52 owing to the inherent resiliency of the flap, automatically moves downwardly over the outside of the edge 47 of the recess into the position shown in Fig. 3, whereby 70 the flaps 38 and 39 are locked in their respective assembled positions, and cannot accidentally be opened.

It will be understood that the user who inserts the contents into the box, will unfold the

various flaps excepting the flap 37, to extend the box from its collapsed position into the position in which the filled boxes are shipped. In its collapsed position, the various flaps of the box are not folded, excepting that the flap 37 has been secured in place to the side 19, and the doubled cover has been folded about the line 18 on to the remainder of the collapsed blank, thereby forming a collapsed box whose width is that of the top plus the width of one side, and whose length is the length of the cover plus the lengths of the various flaps.

After the user has arranged the flaps in the manner described and has folded the parts 63 and 64 into their proper supporting positions, the contents are inserted into the container portion of the box, being held in place by the ledge 36 and the extensions thereof 34 and 35. The tab 77 is then lifted and the cover 20 folded down on top of the ledge while the tab is forced through the slit 75, so that the filled boxes may be shipped to the merchant. The merchant need only open the cover 20 by pulling the tab 77 out of its slit. The cover falls slightly back of the hinge line 18 into the position shown in Fig. 1, whereby the contents of the box are displayed to the purchaser.

It will be understood that the fold line 18 is of such depth that while the cover 20 may be folded into an inclined position past the vertical 30 plane of the rear wall 19, the cover itself is maintained in a self-inclined position owing to the resistance to folding offered by the partly scored fold line 18, whereby the cover is automatically held in its proper display position.

It will further be understood that both sides of the cover as well as the entire outer or exposed surface of the box may be suitably printed by the printing of the under surface of the blank 10 only, and without necessitating the printing of both sides of the blank. The parts 63 and 64 may be omitted if desired, by severing along the lines 61 and 68, and the tab 77 and slit 75 may also be omitted.

It will be seen that my invention provides a simple and comparatively inexpensive box well adapted for display purposes, as well as shipping purposes, and forming an efficient and secure holding means for the contents thereof.

While there has been shown a specific embodiment of the invention, there is no intention to limit the claims thereto, but it is intended to claim the invention as broadly as may be permitted by the state of the prior art and the scope of the appended claims.

I claim:

1. A one-piece combined display and shipping box comprising a container part and an imperforate cover part hinged integrally at its lower edge to the upper rear edge of the container part, said container part having a top wall thereon, provided with an opening, part of the material removed from the top wall to form the opening being separated by a slit into a front part and a rear part, the front portion of the rear part and the rear portion of the front part being bent into horizontal position against the top wall, and the remainders of said parts being bent into vertical position to form a support for the adjacent part of said top wall, and flaps extending integrally from the end edges of the top wall and forming the end walls of said container part.

2. A box of a single sheet of paper comprising a hinged cover of double thickness, the outer of

said thicknesses being imperforate, a container part having front and rear walls, end walls, a bottom and top wall provided with an opening, and a score line at the junction of the outer thickness of the cover and said rear walls, said score line being of insufficient depth to permit movement of the cover through an angle of 180°, but sufficient to permit movement of the cover through an angle greater than 90° and less than 180°, whereby said cover when so moved is self-maintained by gravity in an inclined position, said cover being hinged at said score line to close down on and to completely cover the top wall, the thicknesses of said cover being secured together over substantially their entire areas.

3. In a one-piece combined display and shipping box, a cover part folded on itself to provide two adhering thicknesses of material and coextensive with the container part, a container part hinged integrally at its rear edge to the lower edge of the cover part, a score line between said parts of sufficient depth to permit said cover part to be sustained solely by gravity in a backwardly inclined display position under the weight put upon the outer thickness of said cover by the adhering inner thickness, said container part having a top wall provided with a substantially central opening, adapted to be completely closed by the cover when moved from its display position.

4. A combined shipping and display box of a single piece of material and comprising a cover of two adhering thicknesses of material having an integral bend at the upper edge thereof and hinged at the lower edge thereof, a score line at said lower edge of sufficient depth to permit the movement of the cover through an angle slightly greater than 90° into an inclined display position and to be maintained by gravity in said position, a rear side extending from the outermost thickness of the cover, a bottom extending integrally from the lower edge of the rear side, a front side extending integrally from the front edge of the bottom, a top extending integrally from the upper edge of the front side, said top having an opening 15 therein forming a ledge around the box, the material of said top removed to form said opening being divided in a rear and front part by a slit, the rear part being first bent into contact with the rear part of said top and then bent vertically 20 into contact with the rear side, the front part being bent horizontally into contact with the front part of said top and then into contact with said front side, said cover when swung about the score line down on said top completely covering 25 said opening and said ledge.

MEYER M. SOYBEL.
